ATTORNEY

UNITED STATES PATENT OFFICE.

FLOYD H. HATFIELD, OF RAWLINS, WYOMING.

CASING CONNECTOR.

Application filed May 6, 1921. Serial No. 467,261.

To all whom it may concern:

Be it known that I, FLOYD H. HATFIELD, a citizen of the United States, residing at Rawlins, in the county of Carbon and State 5 of Wyoming, have invented new and useful Improvements in Casing Connectors, of which the following is a specification.

This invention relates to a device for connecting together two parts of a well casing, 10 the parts of which have become disconnected, so that the entire casing can be removed from the well.

By my invention the danger of the walls of the well caving in after the upper section 15 of the casing has been removed is eliminated, as both sections are removed together.

An object of the invention is to provide a device adapted to be lowered into the casing with spring pressed means for forcing gripping members into engagement with the walls of the upper part of the casing, such means being automatically actuated when they reach the point of separation of the 20 two parts of the casing.

25 A further object of the invention is to provide means whereby the device can have a casing spear attached to its lower end and a cable socket attached to its upper end so that the device can be readily lowered into 30 the casing.

This invention also consists in certain other features of construction and in the combination and arrangement of the several parts, to be hereinafter fully described, illustrated in the accompanying drawings and 35 specifically pointed out in the appended claims.

In describing my invention in detail, reference will be had to the accompanying 40 drawings wherein like characters denote like or corresponding parts throughout the several views, and in which:—

Figure 1 is a sectional view showing my invention in use.

45 Figure 2 is a longitudinal sectional view of the device itself.

Figure 3 is a sectional view of the body of the device.

50 Figure 4 is a sectional view of the movable parts.

Figure 5 is a section on line 5—5 of Figure 4.

Figure 6 is a section on line 6—6 of Figure 2.

Figure 7 is a section on line 7—7 of Figure 2.

As shown in these views the device consists of a body A formed of the parts 1 and 2 screw threadedly connected together and the rod 3 fitting in the bore 4 of the body 60 and carrying the keys 5 to which the lugs 6 and the slips 7 are connected. Part 1 of the body is provided with a tapered portion 8 which is provided with opposing flat walls 9, each having a dove-tailed recess 10 therein. The slips 7 are of segmental shape and are slidably mounted upon said flat walls. Each slip is provided with a dove tailed projection 11 which engages the dove-tailed groove 10. The tapered part 8 is provided 70 with a slot 12 in which the key 5 works. Part 2 is also provided with a slot 13 in which the other key 5 works and this portion of part 2 is provided with diametrically arranged longitudinally extending grooves 75 14 for receiving the lugs 6, the side walls of the grooves being provided with the guiding grooves 15 for receiving the small projections 16 on the lugs, said projections being so formed as to permit rocking movement 80 of the lugs upon the reduced ends of the key. The lower ends of the grooves 14 are deepened, as at 17, to receive the extension 6' of the lugs, when said lugs are in inoperative position or in lowered position. A 85

spring 18 is coiled around the lower part of the rod 3 and bears against the lower part of the wall 4 in part 2 and against a shoulder or washer on the rod, this spring tending to force the rod upwardly with the slips and 90 lugs at the upper part of the guides and in operative position. The lower end of the rod 3 is provided with a screw threaded socket 19 for receiving the screw threaded end of the draw rod 20 which is adapted to 95 be inserted through the screw threaded socket 21 and the small lower end 22 of the bore 4 in part 2.

The socket 21 is adapted to receive the screw threaded end of the casing spear B 100 which is provided with the toothed parts 23 for engaging the lower part of the casing. The upper end of part 1 of the body is provided with a screw threaded extremity 24

for permitting it to be attached to the rope socket C so that the entire device can be lowered into the casing by means of a cable 25.

5 The rod 3 with the spring thereon is inserted into the bore of part 2 and the parts 1 and 2 are screwed together. The slips and lugs are then fitted into their guiding grooves and the keys are then driven into place. The rope socket is then screwed to the top of the device and the draw rod 20 is screwed into the rod 3 so that the spring can be compressed sufficiently to bring the working parts to the position shown in 10 Figure 2. A clamp is then placed around the lugs 6 to retain them in this position. The draw rod is then removed and the spear attached. The device is then lowered into the casing and as soon as the lugs enter the 15 casing the clamp is removed as said casing will hold the lugs in the deep parts of their recesses. As soon as the lugs reach the space between the two parts of the casing which are separated, as shown in Figure 1, they 20 are released to such an extent that the spring forces the rod 3 upwardly and this movement will force the slips outwardly and upwardly so that they will grip the upper part of the casing. This upward movement of 25 the rod 3 is communicated to the slips 7 by the key 5, the tapered part 8 acting to force the slips outwardly. At the same time the casing spear attaches itself to the lower portion of the casing by the teeth 23 so that 30 the two parts of the casing are connected together. The casing can then be removed as 35 a whole in the ordinary way.

At present the casing spear is the only tool used for removing casing after it has 40 been parted. In order to use this tool it is necessary for the top part of the casing to be removed from the well before any attempt is made to remove the bottom part. When the top part of the casing is removed the 45 walls of the well frequently cave to the extent that it is necessary to drill out these cavings before the bottom part of the casing is available, and a great deal of delay is often occasioned, and frequently this results in the 50 abandonment of wells.

The draw rod 20 is used for moving the parts into their contracted position so that the device can be lowered into the casing.

It is thought from the foregoing description that the advantages and novel features 55 of my invention will be readily apparent.

I desire it to be understood that I may make changes in the construction and in the combination and arrangement of the several parts, provided that such changes fall within 60 the scope of the appended claims.

What I claim is:—

1. A device for connecting together two parts of a casing comprising a body having a tapered portion and recesses therein, 65 toothed slips engaging the tapered portion, lugs engaging the recesses, spring pressed means for forcing the slips and lugs upwardly and outwardly, such means being held in contracted position by the lugs being 70 held in their recesses by the upper part of the casing until the point of separation is reached when the lugs will be free to permit the spring means to actuate the slips.

2. A device of the class described comprising a body having a tapered portion and a recessed portion, a rod movably mounted in the body, toothed slips engaging the tapered portion, lugs engaging the recessed part, 75 keys connecting the slips and lugs with the rod, a spring for forcing the rod upwardly to move the slips into engagement with the upper part of the casing, said lugs holding the parts in contracted position when in engagement with the upper part of the casing 80 until freed by the parts when the point of separation is reached and means for connecting the device with the lower part of the casing.

3. A device of the class described comprising a body having a tapered part having a 85 slot and groove therein, and another part having a slot and grooves ending in recesses, said body having an interior bore, a rod longitudinally movable in said bore, toothed slips engaging the grooves in the tapered part, lugs engaging the grooves in the other part, keys passing through the slots for connecting the lugs and slips with the rod, a spring on said rod for pressing the same 90 into its upper position to expand the slips, said keys holding the parts in contracted position by being held in the recesses by the upper part of the casing and a toothed spear 95 connected with the lower part of the device.

In testimony whereof I affix my signature. 100

FLOYD H. HATFIELD
